COMBINATION BRASSIÈRE AND CORSET

Christian Dior, Paris, France

Application October 1, 1954, Serial No. 32,499

Claims priority, application France July 30, 1954

Term of patent 14 years

(Cl. D20—2)

To all whom it may concern:

Be it known that I, Christian Dior, a citizen of France and residing at 30 Avenue Montaigne, Paris, France, have invented a new, original and ornamental Design for a Combination Brassière and Corset, of which the following is a specification, reference being made to the accompanying drawing, forming part thereof.

Fig. 1 is a front elevational view of the combination brassière and corset showing my new design;

Fig. 2 is a side elevational view of the combination brassière and corset shown in Fig. 1; and

Fig. 3 is a rear elevational view of the combination brassière and corset shown in Fig. 1.

I claim:

The ornamental design for a combination brassière and corset, substantially as shown.
